(57) **CLAIM**

The ornamental design for a bookmark, as shown and described.

DESCRIPTION

FIG. 1 is a front perspective view of a bookmark, showing my new design; in an environment;

FIG. 2 is a front elevational view thereof without additional environment;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The dot-dash broken lines immediately adjacent to the shaded areas depict the bounds of the claimed design, while all evenly spaced broken lines are directed to environment. The broken lines form no part of the claimed design.
